UNITED STATES PATENT OFFICE.

GEORG GRABE, OF NIKOLASSEE, NEAR BERLIN, GERMANY, ASSIGNEE TO SIEMENS & HALSKE A.-G., OF BERLIN, GERMANY, A CORPORATION OF GERMANY.

TELEPHONE SYSTEM.

1,303,655. Serial No. 795,285, filed October 15, 1913. Specification of Letter Patent. Patented May 13, 1919.

Original application filed October 15, 1913, Serial No. 795,285. Divided and this application filed March 23, 1915, Serial No. 16,424. Renewed August 21, 1918. Serial No. 250,893.

To all whom it may concern:

Be it known that I, GEORG GRABE, a German citizen, and resident of Nikolassee, near Berlin, Germany, have invented certain new and useful Improvements in Telephone Systems, of which the following is a specification.

This invention relates to telephone systems, the present application being a division of my application Ser. No. 795,285, filed October 15, 1913.

In telephone systems having numerous lines originating calls such as subscribers' lines or trunk lines it is known to connect said lines with trunk lines less numerous than said lines by means of switches known as call seekers associated with said trunk lines. Since the number of lines to be tested by a call seeker is usually very large it is necessary that the call seeker run with a high speed.

The object of my invention is to increase the speed of such call seekers by having the adjusting member retained at a desired contact by means of a locking mechanism which is mechanically brought into locking position and retained therein by a change of the magnetic condition of the test electromagnet.

My invention will be more fully understood by reference to the accompanying drawings, in which—

Figure 1 shows a selector at its zero-position in form of a call seeker, provided with an arrangement according to the invention.

Fig. 2 is a diagram showing the connections for the selector according to Fig. 1.

Referring to Fig. 1, on the shaft 1 of a call seeker provided with contact arms and a series of fixed contacts (not shown) is keyed a pulley 2 which is operated by a cord 16. On the shaft 1 is also mounted a ratchet wheel 6 having an escapement in the form of a pawl 7. Said pawl is provided with an extension 8 forming the armature of a test relay P. This extension 8 is retained in its normal position by means of the nose 14 of the bell crank lever 9 having its fulcrum at 10, said lever 9 being arranged adjacent to the core q of the relay R. The cord 16 slides on the pulley 2 as long as the pawl 7 is prevented from moving by the detent

or lever 14. A spring 11 exerts a pull against the attracting force of the electromagnet R. The downward movement of the lever 9 is limited by a stop 12. Since the selector illustrated is a call seeker having no particular zero-position, the selector will remain upon the contact to which it has been adjusted after the connection, has been broken. The selector is provided with a peculiar arrangement in order to prevent starting if it is in a position to engage a free connecting line. Therefore, the test relay must be excited before starting the selector, so that in spite of the escapement 7 being released by the call-relay R the pawl 7 will yet remain in its locked position. The construction of relay R is such that it may close by its contact r the circuit for energizing the relay P, without attracting its armature 9 for releasing the locking member 7 until after a sufficiently strong energization of the relay P, so that the pole-strength of the relay P will be sufficient to retain the pawl 7 in its locking position. For this purpose the core q of the relay R is mounted in a frame 19 of nonmagnetizable material so that upon the relay R becoming excited the magnetic circuit at either pole will still be open. The energization will, however, be sufficient for attracting the armature 20 and closing the contact r. By the armature 20 the yoke required for closing the magnetic circuit will be formed and the field strength of the relay R will thereby be increased to such an extent that it will attract the lever armature 9 for releasing the projection 8 against the action of the spring 11, whereby the escapement 7 is also released.

The mode of operation of the connections shown in Fig. 2 for a call seeker according to this invention is now as follows: If the subscriber X takes off the receiver a circuit will be closed from ground, back contact t₁, subscriber apparatus X, back contact t₂, relay M starting relay A_n, battery to ground, whereby the relays M and A_n will be energized. The relay M closes its working contact m and therewith impresses the testing potential upon the call seeker contact C. In closing the working contact an by the call relay A_n, the call relay R of the free call seeker AS will be excited over the call distributor WS working in a well known manner, said call seeker R as men-

tioned closing first the contact r . If now incidentally the call seeker AS is contacting with a calling line A, B, the relay P will become excited in a circuit from ground to 5 battery, working contact m , one winding of the relay T, contact C, working contact r , test relay P, contact s to ground. The field strength of the relay R will then be increased to such an extent, that it will attract its armature 9. The selector, however, 10 will not be started since the relay P was already excited before the relay R attracted its armature. Therefore, the relay P holds its armature 8 attracted and the escapement 15 7 remains in the position shown. By closing the working contact t_3 of the relay T, which was simultaneously excited in the same circuit with the relay P, the high resistance winding of the relay T is included in the circuit. At the same time the back contacts t_1 and t_2 are opened so that the relays M and An will become deenergized and the starting circuit disconnected. Therefore, the contact m is opened and thus 20 the resistance in the circuit of the relay T increased whereby the calling line will be busy in the known manner. By the energization of the test relay P the working contacts p_1 , p_2 , p_3 will be closed, so that connection is established to the feeding bridge 25 over relay E. By the energization of the relay E the contact e is closed and the slow acting relay V excited. The contacts v and v_2 are closed and the slow acting relay W is excited which will open the back contact W. In the known manner, after deenergizing of the starting relay An the distributor WS will be adjusted upon the next 30 free call finder and the call finder AS now engaged will be busy for any other call. Disconnecting is done in the known manner by opening the contact s whereby the relays P and T will become inoperative. The selector now will not be able to start again 35 because immediately after deenergizing of the relay R the lever 9 will again fall down into its locking position and lock the projection 8 of the escapement 7.

I claim:—

1. In a telephone system, lines originating calls, trunking apparatus, switches less numerous than said lines to connect said lines with said trunking apparatus, said switches comprising a locking device for retaining the adjusting member in a contacting position, mechanical means for bringing said locking device into locking position by the moving force for said adjusting member, and magnetic means for immediately operating said locking member when in locking position.
2. In a telephone system, lines originating calls, trunking apparatus, switches less numerous than said lines to connect said lines with said trunking apparatus, said switches

comprising a locking device for retaining the adjusting member in a contacting position, mechanical means for bringing said locking device into locking position by the moving force for said adjusting member, and magnetic means for immediately operating said locking member when in locking position and at the moment of contact between said adjusting member and said calling line.

3. In a telephone system, lines originating calls, trunking apparatus, switches less numerous than said lines to connect said lines with said trunking apparatus, said switches comprising an adjusting member, a locking device for retaining said adjusting member in a contacting position, mechanical means for bringing said locking member into locking position by the moving force for said adjusting member, a test magnet for immediately operating said locking member when contacting with a calling line, and means for varying the magnetic condition of said test magnet.

4. In a telephone system, lines originating calls, trunking apparatus, switches less numerous than said lines to connect said lines with said trunking apparatus, said switches comprising a locking device for retaining the adjusting member in contacting position, mechanical means for bringing said locking device into locking position by the moving force for said adjusting member, magnetic means for immediately operating said locking member when in locking position, means for energizing said magnetic means at the moment of contacting of the adjusting member with said calling line, said mechanical and magnetic means being arranged so that in said moment said locking member is in its nearest position to said magnetic means.

5. In a telephone system, lines originating calls, trunking apparatus, switches without zero-position less numerous than said lines to connect said lines with said trunking apparatus, said switches comprising a locking device for retaining the adjusting member in a contacting position, mechanical means for bringing said locking device into locking position by the moving force for said adjusting member, and magnetic means for immediately operating said locking member when in locking position.

6. In a telephone system, lines originating calls, trunking apparatus, switches without zero-position less numerous than said lines to connect said lines with said trunking apparatus, said switches comprising a locking device for retaining the adjusting member in a contacting position, mechanical means for bringing said locking device into locking position by the moving force for said adjusting member, magnetic means for immediately operating said locking member

when in locking position, and magnetic means for releasing said locking member.

7. In a telephone system, lines originating calls trunking apparatus, switches without 5 zero-position less numerous than said lines to connect said lines with said trunking apparatus, said switches comprising a locking device for retaining the adjusting member in a contacting position, mechanical 10 means for bringing said locking device into locking position by the moving force for said adjusting member, magnetic means for immediately operating said locking member

when in locking position, magnetic means for releasing said locking member, said magnetic releasing means closing a circuit containing said magnetic means for operating said locking member before releasing said locking member. 15

In testimony whereof I have hereunto set 20 my signature in the presence of two subscribing witnesses.

GEORG GRABE.
